ATTORNEYS

UNITED STATES PATENT OFFICE.

FRANK A. SMITH, OF CHICAGO, ILLINOIS.

DESIGN FOR AN UMBRELLA OR CANE HOLDER.

SPECIFICATION forming part of Design No. 32,373, dated March 20, 1900.

Application filed January 29, 1900. Serial No. 3,234. Term of patent 14 years.

To all whom it may concern.

Be it known that I, FRANK A. SMITH, a citizen of the United States, and a resident of Chicago, in the county of Cook and State of Illinois, have invented and produced a new and original Design for an Umbrella or Cane Holder, of which the following is a full, clear, and exact description.

The invention relates to holders for retaining umbrellas, canes, whips, and other articles of like form, and also cards, tickets, and the like, and wearing-apparel.

Reference is to be had to the accompanying drawing, forming a part of this specification, in which the figure is a perspective view of a holder embodying my new design.

The design in its entirety comprises a cruciform base the members of which are arched, the vertical member being of greater length than the transverse member; also the upper

end of the vertical member is slightly curved outwardly and upwardly and the lower end is recurved in the form of an upwardly-extending hook. A clip extends outwardly from the base at the intersection of its members 25 and is semicircular in form, the ends of the clip flaring outwardly from the contracted opening of the clip.

The leading feature of the design consists in a holder having a cruciform base and the 30 clip extending therefrom.

Having thus described my invention, I claim as new and desire to secure by Letters Patent—

The design for an umbrella or cane holder, 35 as herein shown and described.

FRANK A. SMITH.
